UNITED STATES PATENT OFFICE.

ISIDOR J. KUSEL, OF CHICAGO, ILLINOIS, ASSIGNOR TO STRONGHART COMPANY, OF CHICAGO, ILLINOIS, A CORPORATION OF ILLINOIS.

LOCK FOR SMALL COIN BANKS.

1,413,538.

Specification of Letters Patent. Patented Apr. 18, 1922.

Application filed April 29, 1918. Serial No. 231,347.

To all whom it may concern:

Be it known that I, ISIDOR J. KUSEL, a citizen of the United States, residing at Chicago, in the county of Cook and State 5 of Illinois, have invented a certain new and useful Improvement in Locks for Small Coin Banks, of which the following is a full, clear, concise, and exact description, reference being had to the accompanying 10 drawings, forming a part of this specification.

My invention relates to locks for small coin banks.

The principal object of this invention is 15 to provide a practical and advantageous construction of coin banks, and particularly to provide a novel and improved lock therefor.

Another object of the invention is to 20 simplify the construction and reduce the cost of manufacture.

In the accompanying drawings Fig. 1 is a side elevation of a coin bank embodying my present invention;

25 Fig. 2 is a view of the under side of the bank;

Fig. 3 is a vertical longitudinal section;

Figs. 4 and 5 are cross sections taken on lines 4—4 and 5—5, respectively, in Fig. 3.

30 In the drawings I show a coin bank 1 having a construction of a cartridge or shell such as now commonly used in modern warfare. This construction is hollow, as shown in Figs. 3 and 4, so that the interior of 35 the same forms a space or chamber into which the coins may be introduced. A coin slot is provided and this is preferably located at or near the pointed end of the bank, as shown at 2.

40 The bottom 9 of the bank is preferably made removable so as to form a means for permitting the extraction of the coins. This bottom 9 is preferably provided with an annular ridge or flange 10 into which the 45 lower end portion of the tubular part of the bank fits.

This bottom 9 being removable to permit the removal of the coins in the bank, is provided with means by which it may be 50 locked in position to prevent improper or unwarranted opening of the bank. The locking means shown as a highly desirable and advantageous construction consists of a clip 11 pivoted to the center of the bottom 55 9 by means of a pin 12. The pivotal con-

nection is loose so that the clip 11 may be moved or turned about the pivot 12. The sides of the clip 11 are slightly upturned as at 13. The lower end of the bank tube is provided with inwardly extending lugs 60 or projections 14, preferably two of these located diametrically opposite one another. The clip 11 has its ends separated sufficiently from the bottom 9 to permit room for the lugs 14 between said clip ends and 65 said bottom 9. Thus the bank bottom 9 may be locked in position by causing the clip 11 to be so turned or positioned as to lie over the two lugs or projections 14, whereby said bottom 9 is prevented from being pulled away or separated from the tubular portion of the bank. In order to hold the clip 11 reasonably fixed in position when it has been placed in engagement with the lugs 14, the clip is slightly 70 bent or recessed underneath, as for example by stamping creases 15 in it during the process of manufacture, each end of the clip being provided with two creases 15 separated from one another a distance somewhat 75 greater than the width of the lugs 14, as shown in Fig. 4, the result of such creases being of course to push the metal down somewhat below the creases leaving the intermediate portion somewhat elevated. 80 In order to permit the clip 11 to slide readily over the edges of the lugs 14, the slightly upturned or inclined edges 13 are provided as previously set forth. In Fig. 5 the central portion of the clip 11 is shown somewhat humped or elevated to permit the outer end of the pivot or rivet 12 to be countersunk in the bottom 9; the upturned ends 13 are also shown in this figure. The exposed end 12^a of the rivet appears on the 85 outside of the bottom and suggests the percussion cap of a shell or cartridge, as shown in Fig. 2.

In order to permit the turning of the clip 11 to produce engagement and disengagement of the same with the lugs or projections 14, I provide a key 17 by which the bottom 9 may be turned, the bottom having two apertures 18 on opposite sides of its center, and the key 17 having two fingers 100 or prongs 19 adapted to fit into the apertures 18. These prongs 19 are of such length that they project from the inner surface of the bottom 9 and are adapted to engage the clip 11. Thus when the key is 105 110

applied to the bottom 9 and turned, the bottom 9 is also turned and if the clip 11 is in engagement with the lugs 14 the bottom 9 is very likely to turn without turning the 5 clip 11. However, when the bottom 9 is turned to such an extent that the prongs 19 engage opposite sides of the clip 11, further turning of the key will turn the clip 11 also and thereby cause the clip to be moved 10 out of engagement with the lugs 14, thereby unlocking the bottom 9 and permitting the same to be removed and the bank opened.

It will be seen that the key 17 may be turned in either direction with the same 15 opening effect, inasmuch as no matter what the direction, the prongs 19 will engage the sides of the clip 11, when it is sufficiently turned, and further turning movement will disengage the clip and lugs 14.

20 In order to relock the bank the bottom 9 is put in position and then turned either to one side or the other until the clip 11 engages the projections 14. The key 17 may be used for this purpose if desired, but it 25 is not ordinarily necessary to do so, for a slight rotative movement of the bottom 9 by the fingers is ordinarily sufficient to accomplish the engagement of the locking devices 11 and 14. This engagement can 30 readily be ascertained by the feeling that a locked condition exists which will be observed by the fingers or hands holding the two parts of the bank and adjusting the bottom 9 relatively to the tubular part.

35 It will be understood that changes and modifications may be made without departing from the spirit of the invention.

What I claim is:

40 1. A small bank in the form of a shell or cartridge, the bottom of which is made removable, in combination with the locking means comprising lugs or projections on the lower end of the tubular portion of the bank and a clip on the bottom of the bank, said clip being adapted to be engaged 45 and disengaged with said lugs or projections and being rotatable independently of the bottom, and the bottom having an aperture through which a key may project 50 whereby said clip may be operated by said key projecting through the bottom.

55 2. A small bank in the form of a shell or cartridge, the bottom of which is made removable, in combination with locking means comprising lugs or projections on the lower 60 end of the tubular portion of the bank and a clip on the bottom of said bank, said clip having recessed portions in its ends for tending to maintain engagement with said lugs or projections and also having upturned side portions to facilitate movement of said clip by or over said lugs or projections.

65 3. A small bank provided with locking mechanism comprising lugs or projections on one portion of the bank and a clip on

another portion of the same, said clip being mounted upon said last mentioned portion so as to permit movement of the latter independently of the clip, whereby said portion may be unlocked only by the use of a key 70 or tool projecting through the same.

4. A small bank having a portion of its wall made removable so as to permit removal of the coins, in combination with locking means comprising lugs or projections on the 75 main body portion of the bank and a rotatable clip on the removable portion thereof for engagement with said lugs, said clip being movable independently of said removable portion, and a key having a member adapted to pass through the wall of said removable portion of the bank and engage the clip on the same, whereby said clip may be disengaged and the bank unlocked by said key.

5. A small bank having a removable wall portion arranged and mounted for rotary turning movement relatively to the body portion of the bank, said body portion of the bank being provided with lugs or projections and said openable portion being provided with a clip adapted to engage said lugs or projections and thereby lock said removable portion in position, said clip being mounted loosely upon said removable portion to permit the latter to be rotated without rotating the clip and said removable portion being provided with one or more apertures to permit the insertion of a key or tool to actuate the clip and thereby disengage the same from the lugs or projections and unlock the bank.

6. A small bank having a removable wall portion arranged and mounted for rotary turning movement relatively to the body 105 portion of the bank, said body portion of the bank being provided with lugs or projections and said removable portion being provided with a clip adapted to engage said lugs or projections and thereby lock said removable portion in position, said clip being mounted loosely upon said removable portion to permit the latter to be rotated without rotating the clip, and a key or tool 110 adapted to be inserted through said removable portion to permit the same to be rotated and the clip to be engaged and disengaged from the lugs or projections, thereby unlocking the bank.

7. In a small bank, locking mechanism 120 comprising a lug or projection and a rotatable clip for engaging and disengaging said lug or projection, said bank being provided with an aperture through which a key or instrument may be inserted to rotate 125 said clip to disengage it from said projection and thereby unlock the bank.

8. A small bank of tubular form having an open end provided with oppositely disposed lugs or projections in combination 130

- with a closure for said open end, said closure being provided with a clip pivoted between its ends, the ends of said clip being adapted to be moved into and out of engagement with said lugs or projections to lock and unlock said closure, said closure being provided with an aperture through which a key or tool may be inserted to engage and actuate said clip to unlock the bank.
- 10 9. A small bank of tubular form having an open end provided on its inside with lugs or projections, in combination with a closure for said open end, said closure being provided with a rotatable clip adapted to engage said lugs or projections, the closure of the bank having an aperture and a key having a portion adapted for insertion through said aperture to engage the clip and thereby rotate the same to disengage it from the lugs or projections and thereby unlock the bank.
- 10 10. A small bank of tubular form having an open end provided with inwardly extending lugs or projections in combination with a closure for said open end, said closure being mounted and arranged for rotative movement relative to the tubular portion of the bank, a clip mounted on said closure and pivoted between its ends, the latter being adapted for engagement and disengagement with said lugs and projections, said closure being provided with two apertures, one on each side of its center to permit the insertion of prongs of a key whereby said closure and the clip thereon may be turned by the key to unlock the bank.
11. A small bank of tubular form having an open end provided with inwardly extending lugs or projections in combination with a closure for said open end, said closure being mounted and arranged for rotative movement relative to the tubular portion of the bank, a clip mounted on said closure and pivoted between its ends, the latter being adapted for engagement and disengagement with said lugs and projections, said closure being provided with two apertures, one on each side of its center to permit the insertion of prongs of a key, and a key having prongs adapted for insertion into said apertures and projecting inside of said closure so as to engage the clip when the key and closure are turned.
- In witness whereof I hereunto subscribe my name this 16th day of April, A. D. 1918.
- ISIDOR J. KUSEL.
